US00D899170S

(12) **United States Design Patent** (10) **Patent No.:** **US D899,170 S**
(45) **Date of Patent:** **** Oct. 20, 2020**

(54) **INTEGRATED MIXING CUP**

(71) Applicant: **MAPLE LEAF TECHNOLOGY (SHENZHEN) CO., LTD.**, Shenzhen (CN)

(72) Inventor: **Sige Xue**, Shenzhen (CN)

(73) Assignee: **MAPLE LEAF TECHNOLOGY (SHENZHEN) CO., LTD.**, Shenzhen (CN)

(**) Term: **15 Years**

(21) Appl. No.: **29/739,646**

(22) Filed: **Jun. 28, 2020**

(51) LOC (12) Cl. **07-01**

(52) U.S. Cl.

USPC **D7/300.1; D7/511; D7/529; D7/531**

(58) **Field of Classification Search**

USPC D7/507, 509, 510, 511, 513, 529, 531, D7/532, 523, 533, 534, 535, 536, 392.1, D7/296.1, 396.2, 300.1, 608, 300, 320, D7/624.1, 624.2; D3/202; D9/501, 502, D9/503, 504, 530, 529, 522, 554, 567, D9/571, 569, 449, 516

CPC A47G 19/22; A47G 19/2288; A47G 19/2205; A47G 19/2211; A47J 41/0077; A45F 3/16

See application file for complete search history.

Primary Examiner — Jae Liang

(57) **CLAIM**

The ornamental design for an integrated mixing cup, as shown and described.

DESCRIPTION

FIG. 1 is a perspective view of a first embodiment of an integrated mixing cup showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the integrated mixing cup showing my new design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the drawings depict portions of the integrated mixing cup that form no part of the claimed design.

1 Claim, 16 Drawing Sheets
